UNITED STATES PATENT OFFICE.

HARRY G. HECKMANN, OF BINGHAMTON, NEW YORK.

DESIGN FOR AN INTERNALLY-HEATED FLATIRON.

55,791.

Specification for Design.

Patented July 13, 1920.

Application filed October 8, 1919. Serial No. 329,374. Term of patent 7 years.

To all whom it may concern:

Be it known that I, HARRY G. HECKMANN, a citizen of the United States, residing at Binghamton, in the county of Broome and State of New York, have invented a new, original, and ornamental Design for an Internally-Heated Flatiron, of which the following is a specification, reference being had to the accompanying drawing, forming part hereof.

This design comprises a double pointed body the top and sides of which are curved downwardly at gradually increasing rates, from the center toward the ends and sides, as shown, so as to present a pleasing appearance of lightness and symmetry.

Abrupt angles are avoided, the general out-lines of respective ends of the body are substantially identical, and the ends of the flat bottom are inclined somewhat upwardly.

A handle is supported above the top of the body by means of a curved strap, same being so formed as to harmonize with the out-lines of the body.

The shield *s*, not being essential, may be omitted if desired.

What I claim and desire to secure by Letters Patent of the United States is:

The ornamental design for an internally heated flatiron substantially as shown and described.

HARRY G. HECKMANN.
